UNITED STATES PATENT OFFICE.

PETER WIEDERER, OF STAPLETON, NEW YORK.

DESIGN FOR A PICTURE-FRAME.

SPECIFICATION forming part of Design No. 22,459, dated May 23, 1893.

Application filed April 11, 1893. Serial No. 469,964. Term of patent 3½ years.

To all whom it may concern:

Be it known that I, PETER WIEDERER, a citizen of the United States, residing at Stapleton, in the county of Richmond, State of New York, have invented a new and original Design for Frames, of which the following is a specification.

In the accompanying drawing a face-view of a frame of my new and original design is shown.

The leading feature of my design consists of representations of the buildings of the World's Fair, produced in relief around a central opening for a picture, mirror, &c., to be held by the frame.

A is the central opening, B a scalloped border of the same. C, in the upper left-hand corner of the frame, is the representation in relief of the Administration building of the World's Fair in Chicago; D, in the lower left-hand corner, is a representation in relief of the Art building of the World's Fair; E, in the upper right-hand corner is a representation of the Woman's building; F, in the lower right-hand corner, a representation of the Mechanical Arts building; G, in the center of

the bottom of the frame, a representation of the battle ship at the Fair; H, in the center of the top of the frame, a representation of an angel seated on a globe and holding the United States shield; J, at the center of the left-hand part of the frame, is the representation of the colonnades in front of the Machinery building; K, at the center of the left-hand part of the frame, is the representation of one of the bridges and gondolas. The several buildings are surrounded by arabesques of the rococo style and L L are fields of diamonds or fret-work between the several representations of buildings.

Having thus described my invention, I claim as new and desire to secure by Letters Patent—

The design for a frame, substantially as herein shown and described.

In testimony that I claim the foregoing as my invention I have signed my name in presence of two subscribing witnesses.

PETER WIEDERER.
